[57] CLAIM

The ornamental design for a cap stretcher, as shown
and described.

DESCRIPTION

FIG. 1 is a front elevational view of a cap stretcher,
showing my new design.

FIG. 2 is a rear elevational view.

FIG. 3 is a left side elevational view.

FIG. 4 is a top plan view.

FIG. 5 is a bottom plan view thereof.

The appearance of the right side is a mirror image of the
left side shown in FIG. 3.

FIG. 1

FIG. 2

FIG. 3

FIG. 4

FIG. 5
